(57) CLAIM

I claim the ornamental design for a side chair, as shown and described.

DESCRIPTION

FIG. 1 is a perspective view of my side chair;

FIG. 2 is a front view thereof;

FIG. 3 is a right side view, the left side (not shown) is a mirror image thereof;

FIG. 4 is a rear view thereof; and,

FIG. 5 is a top view of my side chair.
